MEANS FOR OPERATING UPON HIDES,
SKINS, AND LEATHERJohn H. Connor, Newton, Mass., assignor to The
Tanning Process Company, Boston, Mass., a
corporation of Massachusetts

Application June 24, 1933, Serial No. 677,357

23 Claims. (Cl. 149—16)

This invention relates to means for operating upon hides, skins, leather and other similar pieces of work. While the invention is illustrated as embodied in a machine for performing putting-out operations upon hides and skins it is to be understood that the invention and various important features thereof may have other applications and uses.

It is an object of the invention to improve tannery machines of the type wherein substantially one-half of a given piece of work is operated upon during a cycle of the machine after which the work is reversed in position and reintroduced to secure treatment of the other half of the piece of work. Another object is to expedite handling of the pieces of work so that the operator may be delayed as little as possible in presenting successive pieces of work to the machine, it being clear that the productive capacity of a machine is determined in part by the length of the intervals between introductions of pieces of work, the shorter such intervals on the average the greater the output. It is a further object of the invention to make provision for assisting the operator in positioning the work in such manner that effort to this end, on the part of the operator, is substantially reduced.

To these ends and in accordance with an important feature of the invention, there is provided in the illustrated machine means for receiving each piece of work as it is being operated upon and holding it in such condition that it may subsequently be readily picked up by the operator for introduction into the same or another similar machine for completion of treatment of the work pieces. By this means the work of the operator is facilitated and he is relieved of the necessity of waiting for the machine to operate upon a piece of work introduced therein, since the work-receiving means takes care of the work coming from the machine. Hence, he may promptly turn his attention to the introduction of a fresh piece of work and thus secure practically continuous operation of the machine up to its full capacity. The receiving and holding means referred to may conveniently be utilized as a stacker, whereby a suitable number of pieces may be allowed to accumulate upon the work receiving means before they are removed for introduction a second time into the same or a similar machine to complete treatment of each piece. Alternatively, the completely treated pieces of work may be allowed to accumulate on the receiving means serving as a stacker before removing them for treatment by another ma-

chine in the line of machines provided for operating upon hides and skins. As illustrated, the work receiving means or stacker is embodied in a machine designed to operate upon pieces of work as the latter move away from the operator during machine treatment thereof, and comprises a carrier movable in timed relation to a work support which operates between a work receiving position and a work presenting position with respect to a work treating tool, the said carrier having a crossbar operated to receive each treated piece of work from the work support and hold it suspended in such position that it may be most readily picked up by the operator for reintroduction into the same or a similar machine.

Preferably and as illustrated, a feeding-in table of special construction is provided to facilitate proper positioning of the work by the operator for treatment by the machine, said table tending also to maintain proper positioning of the work as the latter is fed thereover. These features of construction furnish additional reasons why it is possible for the operator to keep the machine constantly working at capacity.

The above-mentioned and other important features of the invention and novel combinations of parts will now be described in detail in the specification and then pointed out more particularly in the appended claims.

In the drawings, Fig. 1 is a view in side elevation and partly in section of a putting-out machine illustrating one embodiment of the invention;

Fig. 2 is a similar view showing the work support in work receiving position;

Fig. 3 is a section taken along the line III—III of Fig. 2; and

Fig. 4 is a sectional view taken along the line IV—IV of Fig. 2.

In the illustrated machine, which is specially designed to perform putting-out operations upon hides and skins, there is provided a work support comprising a bed roll 10, a feeding-in table 12, and a delivery table 14, the tables 12 and 14 being rotatably carried upon shaft 16 of the bed roll 10, and swing arms 18 being provided with journal bearings to support rotatably the shaft 16. To hold the tables 12 and 14, which are fastened together, at the desired angle while in work receiving and work presenting positions, the table 12 is fitted with projections or brackets, one of which is shown at 19 provided with a stud 21 slidably engaged in a slot 23 in the adjacent end frame of the machine. As the work support moves upwardly and downwardly the position of

the tables 12, 14 is controlled by said slot to maintain the table always at the same inclination to the horizontal. Preferably and as shown the shaft 16 has its journal supports in blocks one 5 of which is shown at 20 in Fig. 1, each block 20 being backed by a spring 22 interposed between the block 20 and an abutment 24 rigidly secured to the swing arm 18. By thus mounting the shaft 16 in spring pressed blocks 20 the bed roll 10 may yield relatively to a work treating tool.

In the illustrated construction the work treating tool is a bladed cylinder 26 especially constructed to perform putting-out operations upon hides and skins. It is to be understood, however, that the bladed cylinder 26 is removably mounted in the frame of the machine so that it may be removed and replaced by any one of several bladed cylinders the blades of which are adapted to perform such operations as fleshing 15 and unhairing. The shaft of the cylinder 26 is mounted in journals provided in the frame of the machine and is driven continuously by power means, not shown. To prevent water or other waste material from being spattered on the operator, the cylinder 26 is protected by a guard 27.

For co-operating with the bed roll 10 in feeding the work there is provided a feed roll 30 mounted upon a shaft 32 carried by blocks one of which is shown at 34 in Fig. 1, each block being backed by 30 a spring 36 so that it may be moved upwardly along a guideway 38 provided in the frame of the machine. By this construction the feed roll 30 is adapted yieldingly to accommodate itself to variations in thickness of the work passing over 35 the bed roll 10. For driving the feed roll 30 there is provided a sprocket wheel 40 about which passes a chain 42, the latter being engaged also with a sprocket 44 fixedly secured to a shaft 46 arranged to be driven continuously while the 40 machine is in operation by power means (not shown). It follows that the feed roll 30 is also driven continuously while the machine is in operation. Conveniently the shaft 32 of the feed roll 30 is provided with a long toothed gear 48 arranged to mesh with a similar gear 50 secured to the shaft 16 of the bed roll 10, the arrangement being such that the two gears 48 and 50 become meshed with each other when the bed roll 10 moves to work presenting position with respect to the feed roll 30 and the bladed cylinder 26. In other words, the bed roll 10 is driven from the feed roll 30 when the bed roll moves into co-operative relation with respect to the bed roll 30 and the bladed cylinder 26, the bed roll 10 being disconnected from the driving means as it moves 55 away from work presenting position toward the work receiving position shown in Fig. 2.

As before stated the bed roll 10 is mounted in swing arms 18 which are pivotally mounted at 54 in the frame of the machine so that the swing arms 18 may be rocked to carry the work support alternately between work receiving and work presenting positions. For thus rocking the swing arms 18 there is provided a pair of pitmen 60 one of which is shown at 56 in Fig. 1 of the drawings, the said pitman 56 being pivoted to the swing arm 18 at 58 and carrying a pair of cam rollers 60, 62, the cam rollers 60, 62 being movable in a vertical slot 64 (Fig. 2) in the adjacent 65 end frame of the machine with the rollers 60, 62 engaging opposite points on a cam 66 rigidly secured to a cam shaft 68 which also carries 70 secured thereto a large gear wheel 70 having teeth arranged constantly in mesh with the teeth 75 of a pinion 72 rotatably mounted on the shaft 46.

When the pinion 72 is clutched to the continuously rotating power shaft 46, the large gear wheel 70 is rotated in the direction of the arrow to cause reciprocation of the pitmen 56 to effect movement of the work support alternately between work receiving and work presenting positions, the work support being retained in its said positions by means under the control of the operator as will be subsequently explained herein.

A hide or skin introduced into the illustrated machine is operated upon throughout substantially one-half of its area after which it must be reintroduced into the machine to complete the treatment upon the remaining half. To facilitate the work of the operator there is provided a work receiving means which receives the work from the work support and holds it in a position such that the operator may readily lift it into position for a succeeding operation. This work receiving and holding means comprises, as shown, a rod or crossbar 80 of a length substantially greater than the length of the largest hide or skin which the machine is adapted to operate upon. This rod or crossbar 80 is supported at its opposite ends by carrier chains one of which is shown at 82, supported upon a toothed wheel 84 rigidly secured to a shaft 86, the said chain 82 being also engaged with smaller toothed wheels 88 and 90 mounted upon shafts 92 and 94, respectively, so positioned that the chain 82 is caused to travel with its upper run in a horizontal plane whereby a piece of work supported upon the rod or crossbar 80 is carried toward the rear of the machine in such position that it may be readily removed by the operator and furthermore in such position that it is suspended clear of the floor. Conveniently the shaft 94 is mounted in movable blocks one of which is shown at 96, the arrangement being such that the shaft 94 may be adjusted in such manner as to adjust properly the tension of the carrier chains 82. Preferably the rod or crossbar 80 is detachably supported by the chains 82 so that it may be removed with a stack of skins thereon while an empty rod or crossbar is substituted therefor.

For driving the carrier chains 82 there is provided driving means comprising a sprocket wheel 100 keyed to the shaft 86. Around the sprocket wheel 100 there is passed a chain 102 which is also engaged with a sprocket wheel 104 fixedly mounted upon a shaft 106 which has fixedly secured thereto a pinion 108 in mesh with the pinion 72 rotatably mounted on the shaft 46. Hence, when the pinion 72 is clutched to the shaft 46 by a treadle operated clutch 107 the carrier chains 82 are moved in timed relation to the movement of the work support by the swing-arm operating cams 66 on the shaft 68. Upon depression of the treadle 109 the clutch 107 is caused to become operative. At the same time a pin 111 on a spring-pressed lever 113 is moved out of a notch 115 in a stop disk 117, the arrangement being such that the pin 111 will drop into another notch after one-half revolution of the shaft 68 and thus cause disconnection of the clutch. For a more detailed description of the operation a clutch and stop disk of the type herein used reference may be had to United States Letters Patent No. 873,790, granted December 17, 1907 upon application of J. Rood and F. J. Perkins.

Preferably and as shown, a specially constructed feeding-in table is provided to facilitate the work of the operator in properly positioning a piece of work upon the work support as a preliminary to treatment thereof by the bladed cylinder 26.

Upon reference to Fig. 3 of the drawings it will be seen that the work support 12 is convexly curved from end to end thereof so that a hide or skin thrown over the work support comprising the bed 5 roll 10 and tables 12 and 14 will rest in properly spread out condition upon the convexly curved support 12, it being remembered in this connection that each hide or skin served as a covering to a rounded, more or less barrel-shaped, animal 10 body. It is for this reason that the hide or skin will conform to a convexly curved work support more closely than to a plane-surfaced work support. Furthermore, each hide or skin has two shank portions on each side of the backbone line, 15 and these shank portions have a distinct tendency to become folded while passing over the work support commonly provided with machines of the beamhouse type. By providing a convexly curved 20 work supporting surface upon the feeding-in table the shank members are caused to be supported at the proper angle to the backbone line of the skin, thus eliminating folds which otherwise would appear. While this positioning of the shank portions of the hide or skin is not entirely 25 automatic, the convexly curved work support certainly facilitates the work of the operator in smoothing out the shank portions of the skin in proper position for treatment by the bladed cylinder. On the other hand, the delivery table 14 30 may be of the usual flat surfaced type since the work simply slides over this surface in moving toward the receiver or stacker comprising the bar 82 and the carrier chains 82.

In operating the illustrated machine, a piece 35 of work such as a hide or skin 110 is thrown over the work support while the latter is in a position shown in Fig. 2, reasonable care being taken to locate the backbone line of the hide or skin substantially along the line 105 (Fig. 2), that is, 40 along a line parallel to the axis of the bed roll 10 and a little forward of a line formed on the bed roll by projecting a plane vertically through the axis of the shaft 16. The purpose of thus locating the piece of work is to secure operation upon 45 substantially one-half of the hide or skin at the first operation of the machine and so that the hide or skin may be properly supported upon the rod or crossbar 80 with substantially one-half 50 of the hide or skin in suspended relation on each side of said rod or crossbar, thus insuring that the hide or skin will not slip from the supporting rod or crossbar. During the operation of the machine, the piece of work is fed away from the front of the machine by the feed roll 30 and during 55 this feeding movement the crossbar 80 is moved rearwardly at substantially the same rate of movement with the result that when the crossbar 80 reaches the rear end of its upper horizontal path and stops at or about the point 112 (Fig. 1), the treated portion of the work will drop 60 from the delivery table 14, thus leaving the hide or skin entirely supported by the crossbar 80. If the treated portion of the work is still being operated upon when the crossbar 80 reaches the point 65 112 in Fig. 1, the feed roll 30 and the bed roll 10 continue to feed the work past the bladed cylinder 26 until treatment of that half of the work is completed, whereupon it drops from the delivery table 14 and quickly reaches a suspended relation 70 with respect to the crossbar 80. While the work support is returning to work receiving position shown in Fig. 2, the carrier chains 82 are traveling to bring the rod or crossbar 80 to the position shown in Fig. 2. These movements of the work support and carrier are initiated by depression of 75

the treadle 109 operating through the clutch 107 by which the pinion 72 becomes secured for rotation with the shaft 46. At the end of a half revolution of the shaft 68 the clutch is disconnected (by pin 111 falling into one of the notches 115 in the disk 117), leaving the work support stationary in its work receiving position and the carrier chains 82 stationary with the rod or slat 80 in the position shown in Fig. 2. After a piece of work is placed upon the work support in the position described the operator depresses the treadle 109 to start another cycle of operations of the machine, the pinion 72 being again clutched to the shaft 46. As a result of the clutching of the pinion 72 to the shaft 46, the cam shaft 68 is rotated to effect 10 movement of the work support toward work presenting position with respect to the bladed cylinder 26, movement of the carrier chains 82 also taking place so as to bring the rod or crossbar 80 into engaging relation upon the inside surface of 15 the suspended portion of the hide or skin 110 to the left in Fig. 2, that is, into the position shown in Fig. 1. The pinion 72 continues to rotate for a definite period after the work support reaches work presenting position, the cams 66 having concentric portions which hold the work support in work presenting position during this period, the movement of the cam shaft 68 being accompanied also by travel of the carrier chains 82 so that the hide or skin 110 is picked up by the rod or slat 20 25 30 35 40 45 1. In a machine for operating upon hides, skins and pieces of leather, a work treating tool, a work support movable between work receiving position and work presenting position with respect to said tool, and means to receive each piece of work as it is being operated upon and to hold it suspended with substantially half of the work on each side of the line of suspension.
2. In a machine for operating upon hides, skins and pieces of leather, a work treating tool, a work support movable between work receiving position and work presenting position with respect to said tool, and means operated in timed relation to the movement of the work support to receive each piece of work as it is being operated upon and to hold it suspended with substantially half of the work on each side of the line of suspension.
3. In a machine for operating upon hides, skins and pieces of leather, a work treating tool, a work support movable between work receiving position and work presenting position with respect to said tool, and a carrier movable away from and toward the work support in timed relation to the movement of the latter to receive each piece of work from the work support and transport it away therefrom.
4. In a machine for operating upon hides, skins and pieces of leather, a tool for treating the work, a work support movable between work receiving position and work presenting position with respect to the tool, means to feed the work over the work support, and means comprising a rod for receiving each piece of work as it is fed from the work support to support the work suspended substantially half on each side of the rod.
5. In a machine for operating upon hides, skins and pieces of leather, a tool for treating the work, a work support movable between work receiving position and work presenting position with respect to the tool, means to feed the work over the work support, and a carrier movable in directions toward and from the work support and constructed and arranged to receive each piece of work in turn from the work support and to support said piece of work suspended from a transverse median portion thereof.
6. In a machine for operating upon hides, skins and pieces of leather, a work treating tool, a work support movable between work receiving position and work presenting position with respect to said tool, and means operable as a stacker to receive each piece of work as it is being operated upon and to hold it suspended with substantially half of the work on each side of the line of suspension.
7. In a machine for operating upon hides, skins and pieces of leather, a work treating tool, a work support movable between work receiving position and work presenting position with respect to said tool, means to feed the work over the work support, and a stacker movable in timed relation to the movement of the work support to receive each piece of work as it is fed from the work support and support it suspended with about half of the work on each side of the line of suspension.
8. In a machine for operating upon hides, skins and pieces of leather, a rotary cylinder for treating the work, a work support movable between work receiving position and work presenting position with respect to the cylinder, means to feed the work over the work support, and a stacker comprising a rod movable alternately toward and from the work support to receive each piece of work as it is fed from the work support and to support the work suspended substantially half on each side of the rod.
9. In a machine for operating upon hides, skins and pieces of leather, a rotary cylinder for treating the work, a work support movable between work receiving position and work presenting position with respect to the cylinder, means to feed the work over the work support, and a stacker comprising a rod movable into position to receive each piece of work in turn from the work support and movable also in a horizontal plane away from the work support to carry said piece of work to the rear of the machine.
10. In a machine for operating upon hides, skins and pieces of leather, a rotary cylinder for treating the work, a work support movable between work receiving position and work presenting position with respect to the cylinder, means to feed the work over the work support, and a stacker comprising a rod arranged to move in an endless path to engage each piece of work as the latter rests on the work support and to carry the work to the rear of the machine away from the work support.
11. In a machine for operating upon hides, skins and pieces of leather, a rotary cylinder for treating the work, a work support movable between work receiving position and work presenting position with respect to the cylinder, means to feed the work over the work support, a stacker movable toward the work support into position for receiving each piece of work from the work support as the work is fed therefrom and away from the work support to carry the work to the rear of the machine, and interconnected means for moving the stacker in timed relation to the movement of the work support to work presenting position with respect to said cylinder.
12. In a machine for operating upon hides, skins and pieces of leather, a rotary cylinder for treating the work, a work support movable between work receiving position and work presenting position with respect to the rotary cylinder, means for feeding the work over the work support, and a carrier comprising a rod arranged to engage a piece of work at approximately a transverse median line thereof to support the work suspended along said median line, said rod being movable to carry the piece of work to the rear of the machine.
13. In a machine for operating upon hides, skins and pieces of leather, a rotary cylinder for treating the work, a work support movable between work receiving position and work presenting position with respect to the rotary cylinder, means for feeding the work over the work support, work receiving means operated in timed relation to the movement of the work support to receive each piece of work from the work support as the work is fed therefrom and to support the work suspended along a transverse median line thereof, and means to move the work receiving means in an endless path to receive the work and to carry it to the rear of the machine.
14. In a machine for operating upon hides, skins and pieces of leather, a rotary cylinder for operating on the work, a work support movable between work receiving position and work presenting position with respect to said cylinder, a feed roll for co-operation with the work support in feeding the work past the cylinder, means to drive the feed roll continuously, means to move the work support to work presenting position with respect to the cylinder and the feed roll,

means to receive the work from the work support, and means to drive the work receiving means in timed relation to the movement of the work support to work presenting position.

5. 15. In a machine for operating upon hides, skins and pieces of leather, a rotary cylinder for operating on the work, a work support movable between work receiving position and work presenting position with respect to said cylinder, a feed roll for co-operation with the work support in feeding the work past the cylinder, means to drive the feed roll and the rotary cylinder continuously, means to move the work support to work presenting position with respect to the cylinder and the feed roll and to hold it there, means comprising a rod for receiving a piece of work from the work support as it is being moved thereover by the work feeding roll and being treated by said cylinder, and interconnected means for driving the work receiving means and for moving the work support whereby the rod of the work receiving means is always in proper initial position to receive the work from the work support.
10. 16. In a machine for operating upon hides, skins and pieces of leather, a rotary cylinder for treating the work, a work support movable between work receiving position and work presenting position with respect to the rotary cylinder, means to feed the piece of work over the work support in a direction away from the front of the machine, a carrier located at the rear of the work support to receive a piece of work as it is fed from the work support, and means to move the work support to work receiving position and to hold it there during treatment of substantially half of the work, said work support moving means being also connected to said carrier to drive the latter for a predetermined period to cause the carrier to receive a portion of the piece of work being operated upon the work support and carry it rearwardly while the work is still being treated upon the work support.
15. 17. In a machine for operating upon hides, skins and pieces of leather, a rotary cylinder for operating on a piece of work, a work support comprising a bed roll movable to present a piece of work to the cylinder, a feed roll arranged to co-operate with the bed roll in feeding the work, means comprising a cam for moving the work support to work presenting position and maintaining it there during treatment of the work, means comprising a crossbar for receiving each piece of work from the work support and supporting it suspended from said crossbar, interconnected means for driving said cam and the work receiving means in timed relation to each other, said interconnected means being constructed and arranged to stop with the work support supported by the cam in work presenting position, and means for driving the work feeding roll and the cylinder independently of said interconnected means whereby treatment of the work may continue after interruption of the movement of the work support and the work receiving means.
20. 18. In a machine for operating upon hides, skins and pieces of leather, a rotary cylinder for operating on a piece of work, a work support comprising a bed roll for presenting a piece of work to the cylinder, a feed roll arranged to co-operate with the bed roll to feed the work past the cylinder, means comprising a cam for moving the work support to work presenting position with respect to said cylinder and for maintaining it there during treatment of the work, said cam
25. having a concentric portion operative to maintain the work support in work presenting position, work receiving means comprising a crossbar for receiving the piece of work from the work support as it is moved thereover by the work feeding means, and means connected to drive the work receiving means and said cam while said cam moves through an arc substantially equivalent to its concentric portion, the work feeding rolls continuing to feed the work past the cylinder to complete the treatment thereof while the work support remains in work presenting position.
30. 19. In a machine for operating upon hides, skins and pieces of leather, pivotally mounted work support mechanism comprising a bed roll, a table mounted for movement with the bed roll, means for moving the bed roll and table about a common axis alternately between work receiving and work presenting positions with respect to a tool, and means for maintaining the table at the same inclination to the horizontal while it is in work receiving and work presenting positions.
35. 20. In a machine for operating upon hides, skins and pieces of leather, work support mechanism comprising a bed roll, a table mounted for rocking movement about the axis of the bed roll, means for moving the bed roll and table alternately between work receiving and work presenting positions with respect to a tool, and means for rocking the table about the axis of the bed roll to maintain it at the same inclination to the horizontal while it is being moved alternately between work receiving and work presenting positions.
40. 21. In a machine for operating upon hides, skins and pieces of leather, work support mechanism comprising a bed roll, a table mounted for movement with the bed roll, means for moving the bed roll and table alternately between work receiving and work presenting positions with respect to a tool, and means comprising a roller and slot one of which is fixed with respect to the table for maintaining the table at the proper inclination while it is traveling alternately between work receiving and work presenting positions.
45. 22. In a machine for operating upon hides, skins and pieces of leather, work support mechanism comprising a bed roll, a table mounted for rocking movement about the axis of the bed roll, means for moving the bed roll and table alternately between work receiving and work presenting positions with respect to a tool, an idler roll carried by the table, and means comprising a fixed member having a slot for the reception of the idler roll whereby the table is controlled as to its inclination during its movements between work receiving and work presenting positions.
50. 23. In a machine for operating upon hides, skins, and pieces of leather, a rotary cylinder for operating on a piece of work, a bed roll for backing the piece of work against the thrust of the rotary member, and a feeding-in table associated with the bed roll, said feeding-in table having a broad and nearly flat work-supporting surface below the work-supporting surface of the bed roll and at an inclination to a plane passing vertically through the axis of the bed roll, said surface being convexly curved in the direction of the length of the bed roll, whereby pieces of work drawn over the relatively broad work-supporting surface of the feeding-in table are caused to be spread out in proper condition for operation thereon by said rotary cylinder.
